UNITED STATES PATENT OFFICE

OLIVER D. MCLEOD, OF OTTAWA, ONTARIO, CANADA

VALVE-SPRING-COMPRESSING MECHANISM

Application filed July 16, 1928. Serial No. 293,043.

This present invention relates to improvements in valve spring compressing mechanism and appertains particularly to a device of this character that will greatly facilitate the removal of the valves of an internal combustion engine for cleaning, replacement or repair.

When engine poppet valves are to be removed for any purpose, it is necessary to compress the operating spring incident to the removal of the locking key or pin. If the valves are to be ground and all must be removed, it is a long and tedious operation if the spring lifter is to be positioned in line and brought into engagement with each valve individually and too, if the lifter support rests on the head of the valve, as is sometimes the case, it is difficult to rotate the valve stem to bring the locking key or pin into such position that it may be withdrawn readily.

It is within the province of my invention to provide a tool of the nature described that can be mounted securely on an engine block and quickly adjusted to engage and operate on any of a number of valve springs without disturbing or shifting the mounting that is incidentally remote from any of the valve heads so that the operator has ready access thereto and is unimpeded in his work of compressing the springs, withdrawing the locking keys or pins and removing the valves, all of which is more easily and speedily accomplished than has heretofore been possible.

The principal object of the invention is to provide a valve spring compressing mechanism of generally improved design and enhanced utility and a further object is the provision of such a device that is characterized by structural simplicity, greater efficiency and reasonable cost of production, being thereby rendered commercially desirable.

To the accomplishment of these and related objects, as shall become apparent as the description proceeds, my invention resides in the construction, combination and arrangement of parts as shall be hereinafter more fully described, illustrated in the accompanying drawings and pointed out in the claims hereunto appended.

The invention will be best understood and

can be more clearly described, when reference is had to the drawings forming a part of this disclosure wherein like characters indicate like parts throughout the several views.

In the drawings:—

Figure 1 is an elevation of my improved device mounted on an engine block and compressing one of the valve springs thereof;

Figure 2 is an enlarged elevation of the device itself; and

Figures 3, 4, 5 and 6 are detail sections as taken on the lines 3—3, 4—4, 5—5 and 6—6, respectively, of Figure 2.

The device attaches to the engine block from which the valves are to be removed, by a mounting bracket 11 having the flanged swivel base 12, the latter being perforated to receive one of the upstanding stud bolts of the engine block and is there retained by the associated nut being screwed down thereon. A horizontal bridge bar 13 slides transversely through the upper end of the bracket 11 and is of sufficient length to bridge the engine block and reach to valves on the side of the engine remote from the mounting bracket. It is prevented from rotation by a longitudinally extending radial rib or key 14 that runs in a keyway 15 in the bored top of the bracket 11. The distant end of the bridge bar 13 is vertically offset and terminally carries a vertically hinging lock catch 16 that fastens at its fixed end to the base of a horizontally pivoted U 17.

In the perpendicular portion 18 connecting the offset end of the bridge bar 13 with the main portion thereof, a vertically movable manually operable lever 19 is fulcrumed having ratchet teeth 20 on the upper side of its outer end adapted to be selectively engaged by the hinged locking catch 16. The inner end of the lever 19 is split and forked and couples by the links 21 with a collar 22 encircling a post 23 that moves vertically through the bridge bar 13 adjacent the perpendicular portion 18. As the upper end of the post 23 has a series of perforations 24 and a removable pin 25 for selective insertion in any one of these perforations, the length of the post 23 depending below the bridge bar 13 may be easily varied.

The lower end of the upright post 23 is bifurcated with the upper part of the slot 26 therethrough of greater width to accommodate a removable and horizontally slidable 5 arm 27, a transverse bolt 28 being threaded through the legs below the arm 27 and adjustable to regulate the frictional engagement of the legs thereon. A pair of confronting jaw members 29 are securely fastened to opposite sides of the arm 27 at the outer end thereof and are drawn together near their free ends by a spring 30 coiled about a transverse connecting bolt 31 with a cooperating nut 32. The spring nesting pocket 33 thus 10 formed by the confronting jaws 29 may spread to adapt this particular form of spring lifting fork to various size springs but as different types of forks or spring engaging tools are used in conventional practice, it is the 15 intention to provide such replaceable tools of this nature as may be desired, the same being selectively positioned in the slot 26.

As the structural composition of the device has thus been described in detail it should suffice in conclusion to make but brief reference to its use and modus operandi: In use, the mounting bracket 11 is secured to the top of the engine block centrally of the ends and on the side thereof opposite from the valves to be removed; the bar 13 then bridges or extends across over the block to allow the post 23 to depend in proximity to the row of valves, which post is then vertically adjusted by placing the removable pin 25 in the proper opening so that when the said post falls to the bottom of its movement the valve spring engaging seat 33 on the end of the arm 27 is at the required height to slide under the valve coil spring to be compressed and by the longitudinal adjustment of the arm 27 the same is readily brought into proper operative contact with the spring. The lever 19 is now moved downwards and fulcruming on the upright 18 and, through the links 21 and collar connection 22, raises the post 23 thereby compressing the valve spring engaged. The device can be left with the valve spring in this strained or compressed position by hinging the locking catch 16 whereby the operator is afforded the free use of both hands in rotating the valve stem, extracting the spring retaining pin and removing the valve all of which operations are greatly facilitated by the fact that the top or head of the valve is 50 clear and none of the work impeded by the valve spring compressing mechanism that bridges the engine block and leaves the operator clear access to the parts to be reached.

When one valve has been removed and the 55 spring compressor released, the device, without changing its mounting, can be swung into position for and brought into engagement with the next valve spring and so on along the full length of the engine if the device is of sufficient capacity, though obviously, in the

case of a long engine block or otherwise when desired, the device may be shifted in its mounting to enable the spring engaging seat to be more readily brought into engagement with its work. Interchangeable spring engaging forks, of types well known in the art, are selected for employment with varying types of valves and valve operating mechanisms but with these replaceable forks or spring tools this valve spring compressing machine can be used to advantage more easily and with greater speed in connection with this kind of work on most all types of engines that have ordinarily to be dealt with.

From the foregoing description taken in connection with the accompanying drawings, it will be manifest that a valve spring compressing mechanism is provided that will fulfil all the necessary requirements of such a device, but as many changes could be made in the above description and many apparently widely different embodiments of my invention constructed within the scope of the appended claims without departing from the scope thereof, it is intended that all matters contained in the said accompanying specification and drawings shall be interpreted as illustrative and not in a limited sense.

Having thus described my invention, what I claim as new and desire to secure by Letters Patent is:

1. A device of the character described comprising a mounting bracket adapted to be secured to the engine block on the side thereof remote from the valves to be engaged, a horizontal bar sliding longitudinally through said bracket and adapted to bridge across the engine block, an upright extension on the end of said bar, a lever fulcrumed thereon, a valve fork sliding vertically through said bar and means connecting said lever and post so that the movement of the former will operate to raise said post.

2. A device of the character described comprising a mounting bracket adapted to be secured to the engine block on the side thereof remote from the valves to be engaged, a horizontal bar sliding longitudinally through said bracket and adapted to bridge across the engine block, an upright extension on the end of said bar having a horizontally bent top offset from the body of said bar, a locking catch hinged thereon, a lever fulcrumed on said upright extension having ratchet teeth on its upper side adapted to be engaged by said locking catch, a valve fork post sliding vertically through said bar, and means connecting said lever and post so that the movement of the former will operate to raise said post.

3. A valve compressing mechanism comprising a mounting bracket swivelling in a flanged base adapted for firm mounting on an engine block, a bar sliding horizontally in said bracket and held against relative rota-

tion, a vertically offset end on said bar, a hinged locking catch on said offset end, a lever fulcruming on the upstanding portion joining the offset ends of said bar, a collar 5 connected to said lever by links, a vertical post embraced by said collar and sliding through said bar adjacent the upstanding portion on which said lever fulcrums, said post having a series of perforations in its 10 upper end, and a transverse pin for selective placement in said perforations adapted to span the upper rim of said collar.

4. A valve compressing mechanism comprising a mounting bracket swivelling in a flanged base adapted for firm mounting on an engine block, a bar sliding horizontally in said bracket and held against relative rotation, a vertically offset end on said bar, a hinged locking catch on said offset end, a lever 15 fulcruming on the upstanding portion joining the offset end of said bar, with the main portion thereof, a collar connected to said lever by links, a vertical post embraced by said collar and sliding through said bar adjacent the upstanding portion on which said 20 lever fulcrums, said post having a series of perforations in its upper end, a transverse pin for selective placement in said perforations adapted to span the upper rim of said collar, 25 and a removable valve spring engaging fork 30 and a removable valve spring engaging fork adjustably mounted in the lower end of said post.

In testimony whereof I hereunto affix my signature.
